UNITED STATES PATENT OFFICE.

JOHN W. WOODRUFF, OF HAMBURG, NEW YORK.

SILO.

SPECIFICATION forming part of Letters Patent No. 699,998, dated May 13, 1902.

Application filed January 7, 1902. Serial No. 88,783. (No model.)

To all whom it may concern:

Be it known that I, JOHN W. WOODRUFF, a citizen of the United States, residing at Hamburg, in the county of Erie and State of New York, have invented certain new and useful Improvements in Silos; and I do declare the following to be a full, clear, and exact description of the invention, such as will enable others skilled in the art to which it appertains to make and use the same, reference being had to the accompanying drawings, and to the letters of reference marked thereon, which form a part of this specification.

My invention relates to improvements in silos in which cement or concrete is used as the body of the same and which is applied to a metallic cylindrical skeleton framing and united together in a peculiar manner and to which the cement adheres and is retained thereto in a strong and substantial manner.

The object of the invention is to dispense with the burning of the tile silos and also the wooden silos, which are made more expensive in their construction and use than cement or concrete used in the present invention.

To this end the invention consists in the construction and combination of parts, as will be hereinafter more in detail described, and particularly pointed out in the claims.

In the accompanying drawings, to which reference is had and which fully illustrate my invention, Figure 1 is a perspective view of my silo. Fig. 2 is a plan view of the same looking down from the top of the silo. Fig. 3 is a detached view of one of the metallic sliding doors. Fig. 4 is a sectional view looking down from the top of the silo. Fig. 5 is a perspective view of my skeleton framework, and Fig. 6 is a sectional plan view of the working or construction drum or cylinder. Fig. 7 is a detail view of the curved connecting rods or bands of the skeleton framework.

Referring by letter to the drawings, A indicates the silo, the body of which is of cylindrical form and is composed of cement, concrete, or other similar material.

B B B B designate strips or ways secured upon the inside and outside of the silo and each side of a continuous narrow opening extending from the bottom to the top, having formed integral therewith rabbets or grooves b, the rabbeted portion of said ways or strips

projecting out from the wall of the silo, both on the inside and outside of the same at the top thereof, and within which slide a series of 55 concave metallic outer doors C and inner doors C', having perforations D D D D therethrough, through which pins E E are passed as fastening means for said doors. The strips or ways are held in place by means of bolts 60 passing through the ways from the inside to the outside of the silo, having heads on the inner ends of said bolts and nuts on the outer ends. When the doors are raised, they are held up by means of the pins heretofore referred to, and when the pins are withdrawn 65 they drop down and are closed.

F F designate a series of holes (shown clearly in Figs. 1 and 2 of the drawings) formed in the silo extending from the bottom to the 70 top to provide a dead-air chamber to condense the moisture or frost and keep the same from passing to the inside of the silo and spoiling the contents of the same.

G designates a metallic skeleton cylindrical frame composed of one or more T-standards disposed at proper distances apart extending to the full length or height of the silo. Each of the standards has a series of perforations 75 g therein, and through which is passed a series 80 of curved sectional inner rods H, having their ends screw-threaded to take nuts h, by which they are secured to the standards.

I designates a series of outer curved sectional bands having their ends hooked; as at 85 i, which hook over the T-heads of the standards and are firmly secured thereby. These rods and bands are connected in sections from one standard to the other circumferentially and are disposed at suitable distances apart, 90 those sections which connect with the standards at the narrow opening provided for the doorway being out of alignment with the other rods and bands, these being disposed in such manner as to admit of wider spaces for 95 one or more short blocks of wood K, which are of concave form, to be set in for forming the door-openings extending from the bottom to the top of the silo. The cement or concrete which is filled in around these blocks K 100 is then allowed to harden around them. After hardening the blocks are removed, which leaves openings for the doors.

The door-openings and the perforations or

holes F F are formed in the walls of the silo by setting in the filling of cement or concrete in building up the silo by means of a templet or short working metallic cylinder, which 5 will be hereinafter described.

In Fig. 6 I have shown the templet or short working metallic cylinder, which consists of a shell M, having an outer and an inner band or walls m m' and a central hub N, from 10 which project cross-arms n n n n n n n n, projected radially from the central hub.

The skeleton frame heretofore described is seated in the shell or cylinder, and up around this skeleton frame are built the walls of the 15 silo, having the doorways and perforations in the walls clearly shown in Fig. 1 of the drawings. These cross-arms have upon their free ends T-heads, which serve to brace and hold all the parts of the cylinder firmly in 20 place during the operation of filling in the cement or concrete, during which operation the templet or short metallic cylinder is raised upwardly from the bottom to the top about two feet at a time and the cement filled in in 25 sections between these short cylinders or bands and at each step taken is allowed to harden or set sufficiently to hold without the aid of the bands, when the metallic cylinder is raised again and the next step taken, 30 similar to that of the first, and so on until the silo is finished, when the templet is entirely removed.

From the foregoing description it will be readily observed that I attach importance to 35 the advantage derived from the construction of the silo, that a silo constructed from concrete or cement is fireproof in its character. The metal framework being entirely covered by the cement, it will not warp or buckle from 40 the effects of intense heat nor corrode from the action of the silage. The walls being perforated from the bottom to the top, a dead-air space is formed for arresting the frost and moisture, thus keeping the contents of the 45 silo in the highest possible state of preservation. A dead-air chamber is also provided between the inner and outer sliding doors of the series of doors in order to preserve the

carbonic-acid gas which accumulates during the transformation of the contents into silage. It must always be emptied from the top. The 50 series of doors are thus arranged, so as to open from the top to the bottom as the contents are taken out. Another advantage is the dispensing with all seams and joints through 55 which air could possibly enter the silo and spoil the contents, a most important feature in the preservation of succulent food, and a further advantage of the silo is its durability and economy in construction, bringing the 60 silo system within the reach of agriculturists of moderate means.

What I claim, and desire to secure by Letters Patent, is—

1. In a silo composed of a frame formed of 65 upright beams, spaced apart and held by rods, said frame being embedded in concrete, having air-spaces therein, in combination with a series of closable door-openings doors in said 70 openings pins for operating said doors located in the holes in the ways B, said openings extending from top to bottom all substantially as hereinbefore shown and described.

2. In a silo composed of a frame formed of 75 upright beams, spaced apart and held by rods, said frame being embedded in concrete, having air-spaces therein, in combination with a series of closable door-openings extending from top to bottom, doors in said openings 80 pins located in the holes in the ways B, and grooved strips or ways B, on the inner and outer sides of the silo, and each side of a continuous narrow opening extending from top to bottom all substantially as hereinbefore described.

3. A silo composed of a frame formed of 85 upright beams spaced apart and held by rods, said frame being embedded in concrete having air-spaces therein.

In testimony whereof I affix my signature 90 in presence of two witnesses.

JOHN W. WOODRUFF.
